J. J. ANDERSON.

Cooking Stove.

No. 12,474.

Patented March 6, 1855.

UNITED STATES PATENT OFFICE.

J. J. ANDERSON, OF BEAVER, PENNSYLVANIA.

COOK-STOVE.

Specification of Letters Patent No. 12,474, dated March 6, 1855.

To all whom it may concern:

Be it known that I, J. J. ANDERSON, of Beaver, in the county of Beaver and State of Pennsylvania, have invented a new and useful Improvement in Cooking-Stoves; and I do hereby declare that the following is a full, clear, and exact description of the construction and operation of the same, reference being had to the annexed drawing, forming part of this specification, in which—

Figure 1 is a perspective view of the stove. Fig. 2 is a section perpendicular to axis of oven. Fig. 3 is a section of stove on axis of oven.

Similar characters of reference in the several figures denote the same part of the stove.

The principal object of my invention is the construction of cook stoves with the greatest possible convenience for culinary purposes, and so to construct the baking chamber that it shall possess all the advantages of the ordinary brick oven. Besides these improvements I construct the back of the fire chamber so as to favor durability and strength, and construct the ash box and hearth so as to be readily removed for cleaning the return flue.

I make the stove in the form of a flattened cylinder as shown in the drawing, and construct on one of its diameters an oven running entirely through the stove, having an oval top and sides similar to the ordinary brick oven; the top of the stove being furnished with the usual openings for boilers and other utensils.

In the drawing, A is the top, and B the base plates of the stove.

C is the cylindrical vertical portion made up of several plates connected in the usual manner.

D D' are the front doors, and E E are the oven doors.

Running through the stove on one of its diameters, is the oven O, in form somewhat like a semi ellipsoid truncated at each extremity of its transverse axis, and similar to the ordinary out door brick oven. In front of the oven is the fire chamber, containing the grate G; the fire back M of which rests on the outer surface of the oven, and is corrugated longitudinally, as seen in Fig. 2, for giving it strength, and by the holding of ashes in the corrugations adding to the durability of the plate. The

space above the oven communicates with the return flues I I, and with the exit flue F when it is not closed by the damper H. The sides a of the return flues I I are concentric with the circle of the stove and these passages communicate with the portion K of the said return flue leading to the exit flue F; the rear of the ash box forms the front of the return flue; these flues being brought into action when the oven is in use for baking.

J is the hearth and P the ash box connected therewith, so that the removal of the ash box will open the return flues, and no obstruction be offered by the hearth to observation and cleaning of the said flues. The top plate A has openings R for the usual cooking utensils, the number depending on the size of the stove.

The action of this stove is as follows. The ellipsoidal form of the oven will cause the flame and current of heated air and gases, to pass over its ends as well as the center, and thus heat to an equal degree all parts of the oven. The cylindrical form of the interior of the stove, prevents cooling and eddying corners, so common in rectangular and other forms, and facilitates the draft by permitting an unbroken current from the fire chamber and over the ends of the oven. The return flues act as in other stoves of like nature to heat the bottom of the oven, and as their construction and operation are well known need not be here set forth.

The oval or ellipsoidal oven of this stove heated as described, by giving an even degree of heat from all parts of its surface renders the baking qualities of this stove equal to those of the oval brick oven. The advantages which result from this form of oven are dependent to a great extent on the curved interior surface of the stove, for the proper deflection of the heated current so as to pass uniformly over the ends of the oven, and heated to an even degree the entire surface. This form of stove gives greater strength with less weight of metal than other forms, and also admits of the reception of a greater number of utensils at the same time than other forms of the same size, thus rendering a small stove capable of serving the same purpose as a much larger one of another construction; and in this manner becomes an economizer of fuel.

What I claim as my invention and desire to secure by Letters Patent, is—

The construction of the ellipsoidal oven in stoves, as herein set forth, arranged in contact at the front with the horizontally corrugated fine back and detachable ash box.

In testimony whereof, I have hereunto

signed my name before two subscribing witnesses.

J. J. ANDERSON.
